CLAIM

I claim the ornamental design for a straddle mount connector, as shown and described.

DESCRIPTION

FIG. 1 is a rear perspective view of a straddle mount connector showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken line portion of the figures is included to show unclaimed subject matter only and forms no part of the claimed design.
